WILLIAM E. EATON, OF WAKEFIELD, MASSACHUSETTS, ASSIGNOR TO CHATON FIBRE COMPANY.

DUST GUARD.

Application filed February 12, 1923. Serial No. 618,492.

The present invention relates to an improvement in dust guards for cars.

The axle box of a railway car receives the projecting end of a car axle through a hole in the rear end of the box. This hole is required to be larger than the portion of the axle which enters the box in order to permit relative movements of the box and axle, and it has long been the practice to employ 10 a dust guard surrounding the axle at the hole to impede the entrance of dust and dirt into the axle box. For this purpose the box is provided with a dust guard recess open at the top of the box through which a 15 dust guard is inserted into the recess. This dust guard is somewhat longer vertically than laterally, and is usually of rectangular shape with the two lower corners of the rectangle cut away on a circle of which the 20 center of the axle is somewhat higher than the center of curvature. This guard is provided with a hole to receive the axle. Wooden dust guards have been extensively used, the material being such as to yield 25 under excessive pressures of the axle against it and calculated to break in case of extraordinary distortion of the relation between the box and the axle. Ordinarily these wooden dust guards can be used but 30 once. That is to say, when for any reason the box is removed from the car axle, a new dust guard is inserted before the box is replaced, not only because of the enlargement 35 of the hole in the dust guard due to its wear against the axle, but also because it is often found to be broken, or is broken in process of removal. In some cases these wooden dust guards are covered with waste pieces of plush in order to make the guard fit the guard recess more closely for the 40 purpose of holding the parts of the broken guard together to facilitate removal. Sometimes the wooden dust guard is strengthened by staples or corrugated strips of 45 metal at places where it is most likely to be broken.

It has been proposed to use animal hair felt for dust guards, but such dust guards, while they may be made to fit the guard 50 recess of the boxes with elastic pressure, are, owing to the very nature of the material, soon broken and are but infrequently capable of being used a second time. The principal objection to the felt dust guard, however, is the high cost of the guard.

It has been proposed to reinforce felt guards with canvas in order to give greater strength to the guard to reduce its liability to breakage in use, but such reinforcements only enhance the expense to such a degree 60 as to render such guard economically unavailable for use. Such animal hair felt dust guard reinforced with canvas stitched to it is also provided with a metallic spring contrivance for contributing to the holding 65 of the guard in position in the guard recess in the box. This only further increases the cost of the guard and renders it commercially unavailable.

The present invention contemplates a dust 70 guard of which the body portion is absorbent and therefore capable of conveying oil from the bottom of the car box to the entire inner surface of the hole in the guard, and therefore flexurally weak, but it is elastic 75 and compressible so as to yield to the strains exerted upon it in use. This body portion is provided with reinforcing layers on both sides of flexurally strong stiff material to support and strengthen the body portion. It 80 is comparatively noncompressible, as the compressible quality of the dust guard is secured by the body portion and the reinforcing layers are required to have greater 85 flexural strength to support such body portion. Both the body portion and the reinforcing layers are formed of fibro-cellular paper-like material which for the body portion is soft, elastic and compressible, having 90 large voids adapting it to conduct the oil 95 by capillarity from the bottom of the box to the edges of the axle holes. The voids of this material are smaller than the voids of animal hair felt and therefore they convey less oil from the bottom of the box to the 100 edges of the axle hole, and this is a virtue which contributes to the commercial value of the guard because it reduces the amount of oil waste substantially, an item by no means to be overlooked in a device of this 105 character. The reinforcing layers are hard and stiff, have very little capillary capacity to lift oil upward from the bottom of the box, and covering the body portion of the guard on both sides, they prevent the escape 110 of oil from the outer side of the body portion, and confine the escape entirely to the central portion of the edges of the body portion exposed at the axle hole. The body portion and the reinforcing layers are united 115.

2 together by suitable fastening devices. The invention consists in the dust guard herein described and particularly defined in the claim.

5 Referring to the accompanying drawings illustrating the preferred form of the invention, Fig. 1 is a front elevation of the dust guard; Fig. 2 is a side elevation thereof; and Fig. 3 is a section taken on the line 10 3—3, Fig. 1.

The dust guard indicated in a general way by the reference character 1 has the usual outline, and is provided with the usual axle hole in its center. The body portion 15 of the dust guard consists of the layers 2 and 3 of paper-like felt. This felt may be made of cow hair, paper pulp and cotton fibre, as described in the Clapp patent dated August 29, 1922, No. 1,427,263, which is a 20 paper felt consisting of approximately 500 parts cow hair, 550 parts paper pulp, and 150 parts cotton fibre. It is immaterial whether the body portion is formed of two layers 2 and 3, as shown in the drawings, 25 or whether it consists of one layer. Other paper-like felts may be employed for the body portion, such as a paper felt made of leather scraps, paper stock and hair laid up loosely and plumply to form an elastic 30 absorbent material. Another material which may be used to form the body portion of the guard is the ordinary soft leatherboard of commerce, consisting of 80 percent leather and 20 percent paper stock. In fact, it is 35 immaterial, viewed in its broader aspects, what composition of body portion is employed, so long as it is a fibro-cellular, paper-like material, flexurally weak, absorbent, elastic and compressible. The reinforcing 40 layers 4 and 5 are provided to afford structural strength, as well as to reduce the amount of oil shed by the body portion. These reinforcing layers are applied to both 45 sides of the body portion, so that the guard is interchangeable side to side. The preferred material of which these reinforcing 50 layers are made is a fibro-cellular paper-like substance such as fibreboard or relatively hard leatherboard, which is flexurally 55 strong, non-absorbent and non-compressible. This material is durable, will stand great wear, will retain its strength under severe use, and afford adequate support to the body portion of the guard. It is preferred to use this fibro-cellular, paper-like material

for the reinforcing layers because it has those qualities which supplement the qualities of the body portion so that the two materials, combined in the manner described, produce a strong, properly absorbent guard, 60 one which will not wear or cut the axle, which is capable of moving in the dust guard recess, and adapting itself to various relative positions of the axle and box without breakage, and is therefore capable of 65 repeated use. But of great importance in this connection is the low price at which these dust guards may be produced because of the cheapness of these materials.

The several layers are united by rivets 70 set at intervals such that they afford adequate means for uniting the several layers into an integral guard. It will be observed that the rivets compress the body portion at the points where they are set, and that 75 the body portion causes the side of the guard to distend between the rivets. This provides a compressible thickening of the guard, making it substantially thicker at the portions between the rivets than at the 80 rivets, but of an elastic thickness at such inter-rivet places so that when the guard is inserted in the dust guard recess, such expanded portions of the guard act yieldingly to hold the guard in place in the recess. 85

This guard commends itself to the manufacturer by reason of its cheapness and facility of construction. It commends itself to the railway man by reason of its durability and efficiency of operation. This 90 guard is more expensive than wood, and yet is preferred over wood because of its durability. It is preferred over animal hair felt guards because it does not waste the oil nor cut the axle and because it is cheaper. 95

Having thus described the invention, what is claimed is:—

A dust guard for axle boxes comprising a body portion and reinforcing layers on both sides thereof coextensive and conterminous 100 therewith, all of fibro-cellular paper-like material, the body portion being of flexurally weak, absorbent, flexible and compressible character, and the reinforcing layers of relatively stiff, flexurally strong, non-absorbent 105 and non-compressible character compared to the material of the body portion, the layers being united together to form an integral structure.

WILLIAM E. EATON.
